FREIGHT CONTAINER ANCHORING DEVICE

Ridsdale Ellis, New York, N. Y.

Application December 9, 1933, Serial No. 701,614

5 Claims. (Cl. 188—5)

This invention relates to freight containers.

To facilitate the moving of containers they have been provided with wheels which may be retracted after the container has been brought into position on the flat car, truck or other carrying vehicle so that the container may rest firmly and substantially immovably on the latter. When it is desired to move the container off such vehicle the wheels are extended so as to lift the body of the container clear of its supporting surface. This involves the expenditure of considerable work.

One of the principle objects of the present invention is to accomplish the same results as are obtained with retractable wheels with less work. When the container is supported on its wheels the body of the container should be at least three inches above the bottoms of the wheels to enable the container to ride over obstructions and to pass from a surface at one inclination to a surface at another inclination, such as is necessary in moving the container from the ground up a ramp onto a platform. This means that the entire weight of the container, except that of the wheels, must be raised three inches. As containers, when loaded, often weigh upwards of 10,000 lbs. this means considerable work.

If, however, instead of moving the wheels, part of the container base is moved downwardly to lift the container off its wheels, the change from a position in which the clearance is three inches to a position which the container rests immovably on its supporting surface can be brought about by raising the container as a whole a fraction of an inch. This follows from the fact that after the container has been brought into position on a flat car, or truck, the desired immobility is secured as soon as the wheels are clear of the supporting surface. If the latter is perfectly flat the container would only have to be raised 1/100 of an inch. However, to provide for inequalities in the supporting surface the wheels should be raised half an inch or so.

Obviously no work is required, other than that required to overcome friction and the weight of minor parts, to move a part of the container base from a position three inches above the bottom of the wheels to a position level with the bottom of the wheels, or vice versa. The only real work is after such base part takes the weight of the container off its wheels.

One suitable form of construction is illustrated by way of example, in the accompanying drawings, in which:

Fig. 1 is an elevation of the container with the outer side wall removed and parts in section;

Fig. 2 is a section on the line 2—2 of Fig. 1; Fig. 3 is a section on the line 3—3 of Fig. 1; and Fig. 4 is a section on the line 4—4 of Fig. 3.

The container comprises a top 10, outer end walls 11, outer side walls 12 and a bottom 13. Within the walls of the container is a frame comprising unitary rectangular end frames 15 of angular cross-section, as shown in Fig. 3, and bottom side frames 16, also of angular cross-section, as shown in Fig. 2, united to the end frames by steel castings 17. Inner end walls 20 and inner side walls 21 are provided for purposes which will be explained later. A frame 18 of inverted channel cross section extends around the top of the container and closes the space between the inner and outer end and side walls as well as stiffening the container as a whole.

In the spaces between the inner and outer side walls are arranged centrally disposed wheels 22 of large diameter. These wheels are suitably mounted on fixed bearings carried by the side walls. In the same spaces near each end of the container is a pair of castor wheels 23. These wheels enable the container to be moved around readily. When, however, it is desired to anchor the container on a flat car or other support for the container, the container is lifted off its wheels.

For this purpose means are provided for moving a portion of the base of the container downwardly and upwardly with respect to the housing, from a position above to a position below the bottom of the wheels, to lift the wheels out of contact with the container supporting surface and prevent further rolling movement of the container. As shown, the movable part of the base of the container comprises a T-bar 25 extending across each end of the container. These T-bars may be raised and lowered in a variety of ways.

One of the most convenient methods is by means of pairs of toggles 26 and 27. The upper arm or link of each toggle is connected by a bracket 30 to the adjacent end frame 15. The bottoms of the lower arm or link of each toggle is connected to a plunger 31 slidably mounted in one of the corner castings 17. The lower ends of these plungers are pivotally connected to the upstanding flanges of the T-bars by pins 32. The toggles are operated by shafts 35 having right hand threads at one end and left hand threads at the other. These threaded portions of the shafts 35 engage nuts 36 and 37 connected to the adjacent ends of the toggle links 26 and 27 respectively. Rotation of the shaft produces move-

ment of the links 26 and 27 in opposite directions so that there is a minimum of tendency for the shaft to move axially as a whole. Should the container be loaded unevenly so that one end is 5 heavier than the other the thrusts on the shafts will be unbalanced as the container is lifted off its wheels. There will also be unbalanced thrusts whenever one T-bar lifts its end of the container before the other. These unbalanced thrusts are 10 taken by plates 40 held in position by pins 41. As the toggles straighten out the shaft 35 drops and to allow for this movement the outer end walls 11 and end frames 15 are slotted at 42.

The projecting ends of the shafts 35 are 15 squared for the application of a handle or wrench thereto. It will be noted that the two shafts 35 on the two sides of the container are not connected for simultaneous operation, so that first one end of each pair of T-bars are depressed and 20 then the other. The pivotal connection between the T-bars and plungers 31 permits this method of depressing the T-bars.

The castings 17 in which the plungers 31 slide 25 are formed with two side wings or gusset plates 45 and 46 integrally connected at the bottom by the part 47. The bottom side frames 16 are riveted to the plates 46 and parts 47. The end frames 15 are riveted to the plates 45 and welded to the lower part of the castings 17 at 48.

Beneath the parts 47 are arranged the castor 30 wheels 23. Each of these wheels is carried by a pair of curved springs 50 secured to the lower end of a shaft 51 rotatably mounted on the adjacent side frame 16 by a bracket 53. At the top 35 of the shaft 51 is mounted an arm 55 carrying a wheel 56 of the same diameter as the distance between the plates 45 and 46. This wheel is arranged so that its center is directly over the point of contact with the ground of the mid- 40 point of the castor wheel 23. As the result of this construction whenever the castor wheel turns, i. e. changes its plane of rotation with respect to the container, the point of contact of the center of the castor wheel with the ground 45 moves along a line parallel to the side of the container instead of in a circular path with respect to the latter. As the castor wheel starts to move outwardly with respect to the side of the container the wheel 56 starts to pull the 50 shaft 51 inwardly to the same extent and vice versa. Hence in spite of its castor wheels the container will track straight and the castors in reversing will not throw the ends of the container laterally.

As the primary function of the castor wheels 55 is to balance the container on its supporting wheels 22 and prevent teetering, the springs 50 are light. To prevent these springs being overloaded, if not broken, and also to relieve the arms 60 52 of undue strain should the castor wheels for any reason have to take the full load of the container, U-shaped stops 57 are provided. These stops are welded to the castor wheel journals and contact with the under surface of the part 47 65 whenever the springs 50 are compressed to a predetermined extent.

The inner side walls 21 are provided to keep the goods carried by the container out of contact with the wheels 22 toggle arms 26, 27 shaft 70 35 and other parts.

The inner end walls are provided to give an unbroken inner wall extending from the bottom of the container, which is below the top of the 75 T-bars when elevated, to the top of the side walls,

which are above the inwardly projecting flanges of the end frames.

If it is desired to use the containers for perishable goods the inner walls may be made of plywood or other material of low heat conductively 5 as compared with metal. In addition, cork or other insulation may be inserted between the inner and outer end walls and between such parts of the inner and outer side walls as are not occupied by the toggle mechanism, wheels 22 and other parts. Insulation may also be provided on the floor and underside of the roof.

No doors are provided in the ends of the containers and hence the roof or top 10 is detachable 10 so that access may be obtained to the interior of the container. A ring 59 is provided in the middle of the top 10 to allow it to be lifted off and replaced on the container. Rings 60 are provided on the sides of the container to allow 15 it to be lifted as a unit when desired.

I claim:

1. A freight container comprising a housing including a rectangular frame around its lower margin, load-supporting, non-retractable wheels attached to the housing and arranged substantially within the periphery of the container as a whole, a base portion movable downwardly and upwardly with respect to the housing and having a part extending upwardly through an aperture in said frame whereby said base portion is prevented from moving laterally with respect to the housing, and means for moving said base portion from a position above to a position below the bottom of said wheels to transfer the weight 25 of the container from said wheels to said base portion and thereby prevent further rolling movement of the container.

2. A freight container comprising a housing including a rectangular frame around its lower margin, load-supporting, non-retractable wheels attached to the housing, base portions extending substantially the length of the ends of the container movable downwardly and upwardly with respect to the housing, each base portion having 30 a part at each end extending upwardly through an aperture in said frame whereby said base portions are prevented from moving laterally with respect to the housing, and means for moving said base portions from a position above to a position below the bottom of said wheels to transfer the weight of the container from said wheels to said base portions and thereby prevent further rolling movement of the container.

3. A freight container comprising a housing, load-supporting non-retractable wheels attached thereto, posts vertically slidably with respect to the housing, base portions secured to the lower ends of said posts, and toggles at the sides of and above the bottom of the housing for sliding 45 said posts to move said base portions from a position above to a position below the bottoms of the wheels to transfer the weight of the container from said wheels to said base portions and thereby prevent further rolling movement of 50 the container.

4. A freight container comprising a housing, load-supporting non-retractable wheels attached to the sides thereof, base portions including posts 55 slidably mounted adjacent the ends of the containers, said posts being movable upwardly and downwardly with respect to the housing, a toggle adjacent each end of the container for moving said base portions by means of said posts from a position above to a position below the bottoms 60

of the wheels to transfer the weight of the containers from said wheels to said base portions and thereby prevent further rolling movement of the container, and a shaft having oppositely threaded ends for moving the knees of said toggles towards or away from each other simultaneously.

5. A freight container, comprising bottom, end and side walls defining a goods receiving space, the lower part of the side walls being spaced inwardly from the outer margin of the container at the bottom thereof, load-supporting non-re-

tractible wheels arranged within the space between said side walls and said outer margins of the container, base portions movable downwardly and upwardly with respect to the housing and means substantially within the outer margins of the container for moving said base portions from a position above to a position below the bottom of the wheels to transfer the weight of the container from said wheels to said base portions and thereby prevent further rolling movement of the 10 container.
